TAKE-UP ROD

Robert H. Lawson, Pawtucket, R. I., assignor to
Hemphill Company, Central Falls, R. I., a corporation of Massachusetts

Application April 28, 1936, Serial No. 76,777

7 Claims.

(Cl. 66—146)

This case involves a take-up rod such as is commonly used with multi-feed knitting machines, which has a special feature of being extensible so that threading on machines of large size is greatly 5 facilitated.

In the drawings:

Fig. 1 is a section showing part of a knitting machine and one of the extensible take-up rods in operative position; and 10

Fig. 2 is a similar view but showing the rod extended to a position for threading, etc.

Multi-feed knitting machines are sometimes provided with a series of these so-called take-up rods or arms, one for each yarn, the function 15 of the rod being to relieve tension in its particular yarn and to avoid breakage of yarn and frequent stopping of the machine. It would otherwise make the operation of the machine more certain and provide the feeding of yarn under a 20 more even tension. These rods are normally mounted at the top of a multi-feed machine and thus are necessarily somewhat inaccessible to the operator since they are very likely to be out of his reach especially when in their uppermost position. Such take-up rods may swing throughout 25 a definite arc for relieving tension in yarns threaded through them and further, may move throughout an additional extent to actuate electrical or other stop mechanism. Such a construction forms the subject matter of co-pending U. S. application Ser. No. 81,897.

It is the purpose of this invention to construct a take-up rod or arm which will assume normal dimensions when in its operative position and 30 which will perform all the functions of the usual take-up rod, but when it is desired to thread a yarn through the end of any rod, will allow that rod to be extended to a position wherein it may be very easily handled and may be threaded 35 without resort to threading hooks or without standing on a ladder, or otherwise inconveniencing the operator.

Referring to the figures of drawings, post 1 which would extend upwardly from the center 45 of the machine carries a support consisting of a hub 2, spokes 3 and a rim 4 within which a plurality of take-up rods or arms have been pivoted at 5, the point of pivot is determined by a slot cut vertically within the rim 4, one slot for 50 each sweep, and a groove machined about the outer edge of the rim within which has been fitted a wire as indicated at 5 for the sweeps to swing upon. Other convenient mechanical constructions may be resorted to for pivotally 55 mounting these elements.

The take-up rods comprise a rectangular base or holder 6 from which extends a tubular part 7. A wire extension 8 fits within the tubular part 7 and is bent as shown at 9 to carry a porcelain or other yarn guide 10 through which a yarn 11 is threaded, this yarn coming from a cone or other supply. The extension 8 is connected for normal unitary engagement and operation with the tubular part 7 by means of a tension spring 12 attached to each element. The spring serves 10 to draw the extension down into the tubular portion in a telescopic fashion as shown in Fig. 1, but allows it to be withdrawn or extended thereby greatly increasing the length of the arm at such times as it is desired to thread it. The end of the 15 part 8 has been rounded off to allow it to enter the tubular portion with a minimum of effort.

The base or holder 6 has an extension 13 projecting in the opposite direction from the tubular part at which has been attached a spring 14 for 20 the purpose of resiliently holding the rod in the position shown in Fig. 1. This spring 14 has been attached to a clip 15 which is in turn hooked about the rim of a disc 16, the hub 17 of which is fixed to post 1. This disc may be moved along 25 the post for the purpose of simultaneously adjusting all the springs 14. The upper end of the spindle or post 1 carries a conical disc 18 which serves as a stop for each of the take-up rods.

In operation these rods will normally maintain 30 a position up against the stop 18 as shown in Fig. 1, except when excess tension in one of the yarns draws its rod down against the resistance of a spring. This movement of the rod will compensate for all jerks and uneven tendencies in the 35 yarn as it is drawn from a supply by knitting needles or by other devices such as positive feeding wheels or the like.

When it is desired to thread the yarn through the eyelet 10 for any purpose, the operator may 40 reach up with a hooked instrument of some suitable nature and will swing the take-up rod about the pivot 5 until it is in approximately the position shown in Fig. 2. In this position he will draw the extension 8 from the tubular part 7 45 extending the spring as much as is necessary until the eyelet is in an accessible position. The tension in spring 12 will be sufficient to prevent return of the tubular part of the device since the extension 13 will be moved to a position 50 wherein spring 14 although extended, will have very little effect to return the part of the take-up assembly to upright position. This will be evident from an inspection of Fig. 2 wherein the point of connection for the spring to the exten- 55

sion 13 is almost directly above the pivot 5. After threading the take-up rod, the extension 8 will be allowed to telescope within part 1 being drawn and guided therewithin by spring 12, whereupon the rod may be swung back to a position such as it normally occupies. It will be necessary to draw off a little slack yarn and to flip the rod upwardly until the full force of spring 14 may be advantageously exerted.

10 In its broadest aspect this invention involves a take-up rod of the general description of that illustrated and means whereby the rod or a portion of the rod can be swung down and extended to an accessible position for threading.

15 One particular construction has been illustrated and that is to be interpreted as illustrative of the invention and not as limiting the same. The invention is defined in the appended claims.

I claim:

20 1. A take-up rod for machines of the type described comprising a yarn tensioning arm resiliently urged in one direction and means attached to said arm for allowing the same to be displaced along its length and to elongate the 25 said rod so that it will assume an accessible position for the purpose of threading.

2. A take-up rod for machines of the type described having a pivot, an arm through the end of which a yarn is to be threaded and means 30 for resiliently urging said arm in one direction, said arm being extensible axially to substantially increase the length of the same for facilitating threading.

3. A take-up rod for machines of the type described having a pivot, an arm through the end 35 of which a yarn is to be threaded and means for resiliently urging said arm in one direction, said arm comprising a tubular part and an extension

fitting within said tubular part but movable lengthwise thereof for the purpose described.

4. A take-up rod for machines of the type described having a pivot, an arm extending in one direction from said pivot and carrying an eyelet through which a yarn is to be threaded, a short extension in the other direction from said pivot and a spring attached thereto for urging the rod in one direction, said first mentioned arm being constructed in such a manner that it can be 10 readily extended in an axial direction and means for automatically returning the said arm to its original or active position.

5. A take-up rod for machines of the type described having in combination a pivot, an arm 15 extending in one direction and carrying an eyelet through which a yarn is to be threaded and means for resiliently urging said arm in one direction, said arm comprising a tubular part, an extension fitting within said tubular part and 20 extending axially thereof for carrying said eyelet and a spring connected to the extension and the tubular part for drawing the two into telescopic engagement.

6. A take-up arm for machines of the type 25 described having in combination a pivot, an arm extending in one direction from the pivot, said arm being formed in two parts one of the parts being 30 slidable relative to the other so that one part may be extended and means for normally maintaining the two parts in engagement and to resist extension.

7. A take-up arm for machines of the type described having in combination a pivot and an 35 extending arm, said arm being formed in two parts and being extensible, one part being slidable within and axially with respect to the other.

ROBERT H. LAWSON.
